UNITED STATES PATENT OFFICE.

BAPTISTE ICRE, OF NEW YORK, N. Y.

PROPELLER FOR VESSELS.

1,182,014.

Specification of Letters Patent.

Patented May 9, 1916.

Original application filed March 3, 1913, Serial No. 751,875. Divided and this application filed September 4, 1913. Serial No. 788,070.

To all whom it may concern:

Be it known that I, BAPTISTE ICRE, a citizen of the Republic of France, residing in New York, in the borough of Manhattan, county and State of New York, have invented certain new and useful Improvements in Propellers for Vessels, of which the following is a specification.

This invention relates to improvements 10 in propellers for marine vessels of that type in which the feathering blades are rotated in a horizontal plane, and relates more specifically to improvements in the propeller for maritime and river navigation for 15 which Letters Patent were granted to me heretofore on November 22, 1910, No. 976,178, and to the marine propeller for which I made application for Letters Patent on August 19, 1911, Ser. No. 645,029, so 20 that the construction of the propeller is not only adapted for smaller vessels, such as submarine boats, yachts, motor-boats, torpedo-boats and the like, but also in a higher degree for larger vessels, inasmuch as re- 25 pairs can be made to the propeller and its operating mechanisms with great facility while the vessel is afloat without necessitating it to go into drydock; and for this purpose the invention consists of a propeller of 30 the type referred to, in which sleeve-shaped sections forming a cam-track are employed for swinging the feathering blades from the horizontal into vertical position, and vice versa, during their rotation in the hori- 35 zontal plane, said sleeve-shaped sections being located on an upright center-shaft supported within a hollow rotary main-shaft and keyed to the center-shaft, the lower end of which is supported on a plate 40 independently of the main-shaft. The hollow main-shaft is open at the bottom for permitting access and making repairs when necessary to the motion-transmitting mechanisms of the blades and to the sleeve-sec- 45 tions forming the cam-track.

The invention consists further in the use of slide-blocks on the crank-arms of the feathering blades, in place of rollers, said slide-blocks being provided with tapering 50 ends for moving between the sleeves with less friction and wear than the rollers, as will be more fully described hereinafter and finally pointed out in the claims.

In the accompanying drawings, Figure 1 55 represents a vertical central section of my improved propeller for marine vessels adapt-

ed for use in larger vessels, the propeller being located at one side of the vessel. Fig. 2 is a similar section showing a modified construction of my propeller, arranged for 60 adjusting the blades to various angles of inclination, located at the opposite side of the vessel. Fig. 3 is a detail side-view of the sleeve-sections forming a cam-track for actuating the feathering blades of the propeller, drawn on a larger scale. Fig. 3^a, a horizontal section on line 3^a—3^a, showing the key-connection of the sleeve-sections with the center-shaft. Figs. 4 and 5 are respectively a detail top-view and an end- 65 view of one of the slide-blocks applied to the ends of the cranks of the blade-shafts for moving between the sleeve-sections, and Figs. 6 and 7 are side-views, partly in section, of face-plates for the sleeve-sections 70 on the interior center-shaft of the propeller.

Similar letters of reference indicate corresponding parts throughout the several figures of the drawings.

Referring to Figs. 1 and 2 of the drawings, A represents a hollow main-shaft which is mounted to rotate on a vertical axis and which is extended through a horizontal casing C in the side-wall of the hull and supported in position by upper and lower ball- 80 bearings B¹, B², one near the upper end of the shaft and the other below the casing C. The upper ball-bearings B¹ comprise an interior ring b, an exterior ring b¹, suitably supported in the vessel, and interposed anti- 85 friction-balls. The lower ball-bearings B² comprise a ring b² carried by the shaft, an outer ring b³ suitably supported in the space below the casing C, and interposed anti- 90 friction-balls. Packing rings b⁴, b⁵ embrace 95 the main-shaft A and are supported by intermediate plates b⁶ on horizontal slide-plates b⁷, which are located respectively on the top and bottom plates of the casing C and connected by screw-rods b⁸ with stationery brackets b⁹, b¹⁰ attached respectively to the top and bottom plates of the casing C. Screw-nuts b¹¹ are held by said brackets and rotated by suitable gear-wheel trans- 100 missions so as to permit the equal shifting of the slide-plates with the main-shaft in- 105 wardly into the casing after the fastening bolts of the slide-plates and the driving connections of the main-shaft are disconnected, the top and bottom walls of the casing C be- 110 ing provided with openings o, o¹ for this purpose. The middle portion of the hollow

main-shaft A between the top and bottom plates of the casing is provided with radial enlargements or hubs A¹ in which are supported the shanks of the feathering blades D by means of suitable ball-bearings e. Suitable packings in the enlargements are employed for preventing the ingress of water to the interior of the hollow main-shaft, said packings being held in position by means of screw-nuts g. The lower end of the hollow main-shaft A is left open, but a horizontal partition-plate a is arranged below the hubs A¹ for permitting the running of the motion-transmitting part in oil. The upper end of the hollow main-shaft A is connected with a crank-shaft C² to which rotary motion is imparted by suitable connecting rods C³ from the power-shaft of the engine as shown in Figs. 1 and 2. In the center of the hollow main-shaft A is supported a vertical shaft S. The lower end of the center-shaft S is supported by an antifriction thrust-bearing t at the bottom of the hull, which bearing is guided on horizontal ways w when the main-shaft is shifted into the casing C, after its fastening bolts are removed, as shown in Figs. 1 and 2. The upper end of the center-shaft S is supported by an antifriction-neck-bearing in the upper end of the hollow main-shaft.

On the middle portion of the shaft S are mounted two sleeve-sections f, which are attached to the center-shaft S by means of cross-keys f¹, as shown in Fig. 1, or by rings f², as shown in Fig. 2. The sleeve-sections f are provided around their abutting ends with flanges which form a cam-track f³ composed of two lower portions, two upper portions and two intermediate inclined portions, as shown more clearly in Fig. 3. Between the flanges of the sleeve-sections are guided slide-blocks or shoes r that are applied to wrist-pins r¹ of cranks r² which are keyed to the inner reduced ends of the shanks of the blades D. As the hollow main-shaft is rotated and as the slide-blocks or shoes r travel around the sleeve-sections f along the lower, inclined and upper portions of the same, and vice versa, the shanks of the blades are turned on their axis and the blades moved from a horizontal into a vertical position, imparting thereby the driving power to the vessel. A propeller is arranged at each side of the hull, while in smaller vessels the shaft of the propeller passes the keel, the propeller being located below the same. The arrangement of the propellers for larger vessels requires that the bevel-gear mechanism S¹, S², which is employed for axially turning the interior center-shaft with its sleeve-sections, be located below the lower end of the hollow main-shaft, as shown in Figs. 1 and 2, so that the blades can also take a vertical actuating position at the inside of the casings

for quickly interrupting the action of the propeller on the vessel without stopping the engine, or for starting the engine without imparting motion to the vessel, while the reversing of the motion of the vessel is accomplished by reversing the engine, and the turning of the vessel by continuing the motion of one propeller and reversing the other propeller. In larger vessels the axial setting of the center-shaft S relatively to the main-shaft is accomplished by power transmitted to the bevel-gears S¹, S² from the engine of the vessel.

The hollow main-shaft in larger vessels is large enough so that a man can easily reach into its lower end and reach the clamping bolts by which the partition-plate and sleeve-sections are fastened to the main and center shafts A and S, so as to permit the release of and the upward and downward movements of the sleeve-sections on the shaft, whereby repairs to the sleeve-sections and to the actuating mechanism of the blades can be made. The slide-blocks or shoes can then also be changed, if required, and all other parts pertaining to the blades repaired. This can be done without removing the center-shaft and blades, as would be the case when the sleeve-sections are made in one integral piece as in the patent heretofore referred to. When repairs to the propeller have to be made, such as changing a broken blade, or the propeller itself, this work can be made without putting the vessel into drydock, by simply shifting the entire propeller inwardly into the casing at the interior of the vessel. This is accomplished by disconnecting the main-shaft and its slide-plates, moving the propeller inside into the casing C, and then lowering a gate G, so as to exclude the water. The water in the casing is then pumped out and the repairs made as required, after which the gate is reopened and the main-shaft and propeller returned into their former position for work.

As regards the slide-blocks or shoes by which the different movements are imparted from the track on the sleeve-sections to the blades, they have a considerable advantage over the rollers, for the reason that the latter have only a slight bearing at their inner edges of the sleeve-sections, so that they become rapidly worn out by the friction therewith. By substituting slide-blocks having a flat top and bottom and tapering ends for the rollers bearing on the track of the sleeve-sections, and running the slide-blocks and cranks in oil, the wear of the slide-blocks on the sleeve-sections is greatly reduced, so that they last for an indefinite length of time.

The sleeve-sections are provided at their lower, inclined and upper portions with face plates n which are attached by shanks

n^1 extending at right angles thereto through holes in the flanges of the sleeve-sections and attached thereto by screw-nuts n^2 , as shown in Figs. 3, 6 and 7. These face-plates can 5 be readily renewed when worn out by the friction with the slide-blocks and keep thereby the sleeve-sections in proper condition for transmitting the proper feathering motion to the blades.

10 I claim:

1. In a vessel, a casing extending into the hull, having two opposite sides provided with openings therein, said casing being closed at its inner end, a revoluble propeller, 15 having blades thereon disposed within said casing and having its shaft projecting through said openings, and in working position, being situated at the outer end thereof, means securing the said propeller in working position, means for rotating said propeller, removably secured plates, exterior of the said casing, encircling the said propeller, and closing the said openings in operative position of the propeller, means 20 for shifting said propeller, and blades and closing plates inwardly into said casing, upon removal of the securing means therefor, and a gate disposed within the vessel adapted to be moved across the said casing 25 when the propeller is shifted inwardly therein, whereby, when the water is pumped out of the casing, access can be secured to the blades of said propeller.

2. In a vessel, a casing extending into the hull, having two opposite sides, provided 30

with openings therein, said casing being closed at its inner end, a revoluble propeller, comprising a cylindrical shaft projecting through said openings, and blades rotatably mounted radially on said shaft, the said shaft in working position situated at the outer end of said casing, means for rotating said shaft, an auxiliary shaft within said cylindrical shaft for rotating said blades, the outermost blades adapted to assume a 40 working position during rotation of the propeller, the innermost blades adapted to assume a feathering position, means securing the said propeller in working position, removable plates exterior of said casing encircling the said propeller and closing the 45 said openings in operative position of the propeller, means for shifting said propeller, and blades, and closing plates inwardly into said casing upon removal of the 50 securing means therefor, and a sliding gate disposed within the vessel adapted to be moved across the said casing when the propeller is shifted inwardly therein, whereby, when the water is pumped out of said casing, access can be had to the blades of said 55 propeller.

In testimony, that I claim the foregoing as my invention, I have signed my name in presence of two subscribing witnesses.

BAPTISTE ICRE.
